The ornamental design for a collection bottle, as shown and described.

DESCRIPTION

FIG. 1 is a perspective view of a collection bottle showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front view thereof showing the state that the upper cap of collection bottle and the collection bottle are detached from each other.

The dot-dashed broken lines in FIGS. 1 and 7 represent a boundary of the claimed design and form no part of the claimed design. The dashed broken lines are for the purpose of illustrating unclaimed portions of the collection bottle and form no part of the claimed design.
